UNITED STATES PATENT OFFICE.

EDWARD P. HATCH, OF LA GRANGE, ILLINOIS.

TAPING DEVICE.

SPECIFICATION forming part of Letters Patent No. 629,074, dated July 18, 1899.

Application filed April 11, 1896. Serial No. 587,214. (No model.)

To all whom it may concern:

Be it known that I, EDWARD P. HATCH, a citizen of the United States, residing at La Grange, county of Cook, State of Illinois, have 5 invented a certain new and useful Improvement in Taping Devices; and I declare the following to be a full, clear, and exact description of the invention, such as will enable others skilled in the art to which it pertains to make 10 and use the same, reference being had to the accompanying drawings, which form a part of this specification.

In fancy undergarments, particularly for women, it has been customary to provide on 15 the edges around the neck a lace edging in which are cross-bars regularly spaced and to run through or interlace in this edging a ribbon or tape which, extending alternately over and under the bars, forms a puckering-string 20 which may or may not be used as such.

The object of my invention is to provide a 25 mechanism whereby this tape or ribbon may be readily inserted in the edging without the delay incident to the employment of the ordinary bodkin or needle.

The invention consists, primarily, of a bodkin with a flexible or movable head or point to which the tape is attached which when 30 caused to move through the fabric will, because of its movable or flexible point, carry the body of the bodkin, and consequently the tape, above one portion of the fabric and below the next one, and so on.

In the drawings, Figure 1 is a side elevation 35 of a portion of my bodkin. Fig. 2 is a view at right angles to Fig. 1. Figs. 3 and 4 show the relative positions of the bodkin and fabric while the tape is being inserted. Fig. 5 is a perspective view of a piece of fabric 40 with the bodkin being inserted.

In carrying out the invention, A represents 45 a suitable rod or strip of metal of any convenient shape or size, preferably round in cross-section and perhaps an eighth or three-sixteenths of an inch in diameter, more or less. One end *a* is tapered and provided with an enlarged head *a'*, in which is pivoted the movable head or point *B*. To the body *A* the tape 50 may be attached in any suitable way. The head or point *B* is, as will be seen, a sort of triangular shape having the point *b*, the rounded corners *b'*, and the recess *b''*, the cor-

ners *b'* forming stops to limit the play of the point in either direction.

In Figs. 3 and 4, C represents the cross-bars 55 of the fabric or edging into which it is desired to insert the tape.

In Fig. 5 I have shown a section of the fabric with the cross-bars *C* and the bodkin being inserted therein. To accomplish this, the 60 operator takes the bodkin in hand, with the tape attached, and, carrying the body of the bodkin on a straight line parallel with the fabric pushes the point below the first bar *C* of the fabric. Continuing the push, the upper corner *b'* will be brought to bear on the bar *C*, and this will tilt the head or point to the position shown in Fig. 3. This tilting of the head or point *B* carries the point *b* to a plane above the plane of the next bar *C*, so 70 that as the bodkin is pushed along the head or point *B* will be above this next bar *C* and the bearing of the corner *b''* on this bar will tilt the point *b* down for the next bar, and so on. Thus all the operator has to do is to 75 hold the body of the bodkin on a plane parallel with the plane of the fabric and push. It will thus be seen that the present method of alternately raising and lowering the body 80 of the bodkin to bring the point above and below the bars of the fabric or the other method of tilting the entire bodkin to accomplish this purpose is obviated.

It is obvious that it is not essential in the 85 operation of my machine that the fabric be held stationary and the bodkin moved through it, since other arrangements of the parts might be made without departing from the spirit of the invention, the essential feature so far as the operation is concerned being the 90 movement of the bodkin and fabric relatively to each other.

What I claim is—

1. In an edging-threading machine, a bodkin arranged to carry the ribbon, a vibrating 95 head supported at the forward end of said bodkin, and means whereby the point of said head is passed under and over each successive bar in the edging as the bodkin is advanced, substantially as described.

2. In an edging-threading machine a bodkin arranged to carry the ribbon, a vibrating head supported at the forward end of said bodkin and means carried by said head where-

2
by the point of said head is passed over and under each successive bar in the edging as the bodkin is advanced, substantially as described.

5 3. A bodkin provided with a vibrating head, said head being provided with a point and with wings or projections extending outwardly and at the rear of said point whereby the point of the head is controlled with respect to the axial line of the bodkin by alternate pressure first upon one wing and then upon the other, substantially as described.

10 4. A bodkin provided with a head movable with respect to the longitudinal axis of said

bodkin, said head being provided with wings 15 or projections, extending to the rear of the point at which the head is held upon the end of the bodkin whereby the point of the head is controlled with respect to the axial line of the bodkin by alternate pressure, first upon 20 one wing and then upon the other.

In testimony whereof I sign this specification in the presence of two witnesses.

EDWARD P. HATCH.
